UNITED STATES PATENT OFFICE.

MAX SCHIESSE, OF BADEN, SWITZERLAND, ASSIGNOR TO AKTIENGESELLSCHAFT BROWN, BOVERI AND CIE., OF BADEN, SWITZERLAND.

CENTRIFUGAL STARTER FOR ELECTRIC MOTORS.

Application filed January 13, 1925, Serial No. 2,189, and in Germany January 26, 1924.

Centrifugal starters for electric motors with rotating strating resistances have been known, the movable contacts of which themselves form the centrifugal weights and at a predetermined angular velocity are pressed upon the stationary contacts against the resistance of a spring. One of these known constructions exhibits as its special characteristic the decrease in the distance between the axis of the spring and the axis of rotation of the movable contacts during their closing movement, the contact arms being constructed as one-armed levers. Now in the design and construction of the contacts one is not altogether free, because regard must be had to a whole series of conditions, and it is therefore not possible to subordinate the size, mass and shape of the contacts merely to the requirements of the centrifugal-force law. In the case of high-speed motors the centrifugal force acting upon the contacts necessitates the provision of powerful opposing springs.

According to the present invention, therefore, counter-weights are arranged on a second arm of the contact lever, and these counter-weights serve to relieve the springs, so that they may be constructed weaker. This may be carried so far that the contact lever is completely counter-balanced, and for the demands of the apparatus only the centrifugal force of the springs is the determining factor.

In the drawing are illustrated in longitudinal section two constructional examples of the invention; in this drawing 1 denotes the motor shaft, 2 the carrier, secured to the shaft, for the contact device, 3 the stationary contacts, 4 the movable contact arms, which are rockable about the pivot 5 and which, by the position thereof, become the two-armed lever, with the contact piece 7 secured to the yielding support 8, and 9 the spring. In addition there is the counter-balancing weight 10, which according to Figure 1 is specially mounted on the short arm of the contact lever 4, but in the example according to Figure 2 is formed by the short lever arm itself, and there serves also as a point of attachment for the spring 9.

In the case of Figure 2 the spring 9 engages at the bent-up end of the otherwise straight lever 4.

What I claim is:

1. A centrifugal switch for mounting on a

shaft of an electrical motor comprising a hub member adapted to be secured to the shaft, a bell-shaped cylindrical body supported on said hub member and enclosing a cylindrical space around said shaft, a double-armed lever pivotally mounted on said bell-shaped body at a point away from the closed end thereof, a spring supported at said closed end and acting on one arm of said lever, a contact member on the other arm of said lever arranged to move with said arm outwardly under the action of the centrifugal force in opposition to the action of said spring, the pivotal mounting of said arm causing said movement to be in a plane through the shaft, and contact members on said bell-shaped body adapted to be engaged by the contact member of said lever arm, the mass of the movable contact member and the associated lever arm being substantially counter-weighted by the mass associated with the other arm of said lever.

2. In a centrifugal switch, a hub member adapted to be mounted on a shaft, a bell-shaped cylinder extending from said hub member and overhanging the same to define a cylindrical hollow space between said hub member and said cylinder, a bell crank lever supported near the open end of said cylinder for pivotal movement in a plane through said shaft, one arm of said lever being disposed toward said hollow space, a spring supported from the closed end of said bell-shaped cylinder to press said arm toward said hollow space, a stop on said hub member for limiting the movement of said arm toward said hollow space, a moving contact member on the other arm of said lever arranged to move outwardly under the action of the centrifugal force in opposition to the action of the spring on said first-mentioned arm, and stationary contact members on said cylinder adapted to be engaged by said moving contact member, said arms being so arranged with respect to the pivotal support thereof that the centrifugal force acting on the mass of the moving contact member and the associated arm is substantially counter-balanced by the centrifugal force acting on the mass associated with the spring-pressed arm of said lever.

In testimony whereof I have signed my name to this specification.

M. SCHIESSE,
